UNITED STATES PATENT OFFICE.

CHARLES H. SHERMAN, OF NORTH ATTLEBORO, MASSACHUSETTS.

DESIGN FOR A SLIDE FOR RIBBON WALDEMAR, SAUTOIR, OR THE LIKE.

58,835.

Specification for Design.

Patented Aug. 30, 1921.

Application filed March 16, 1920. Serial No. 366,429. Term of patent 7 years.

To all whom it may concern:

Be it known that I, CHARLES H. SHERMAN, a citizen of the United States, residing at North Attleboro, in the county of Bristol, State of Massachusetts, have invented a new, original, and ornamental Design for a Slide for Ribbon Waldemars, Sautoirs, or the like, of which the following is a specification, reference being had to the accompanying drawing, forming a part thereof, in which:

Figure 1 is a front view of a slide illustrating my new design;

Fig. 2, an edge view of the slide; and Fig. 3, a sectional view of the same taken on line $x-x$ of Fig. 1.

The essential feature of my new design consists in the convexed or crowned form of its front portion.

I claim:—

The ornamental design for a slide for ribbon waldemar, sautoir, or the like, substantially as shown in the drawing.

CHARLES H. SHERMAN.
